UNITED STATES PATENT OFFICE.

EMILIO QUEROL Y DELGADO, OF BROOKLYN, NEW YORK, ASSIGNOR TO HIMSELF, JAMES WRIGHT, ELIAS DURLACH, AND MORRIS BOOKMAN, ALL OF SAME PLACE.

TENSION FOR SEWING-MACHINES.

SPECIFICATION forming part of Letters Patent No. 377,517, dated February 7, 1888.

Application filed December 3, 1887. Serial No. 256,886. (No model.)

To all whom it may concern:

Be it known that I, EMILIO QUEROL Y DELGADO, a subject of the King of Spain, at present residing in Brooklyn, in the county of 5 Kings and State of New York, have invented a new and Improved Tension for Sewing-Machines, of which the following is a full, clear, and exact description.

The invention relates to a sewing-machine 10 for which Letters Patent of the United States were filed by me on January 21, 1887, Serial No. 225,024.

The object of this invention is to provide a 15 new and improved tension which is very simple and durable in construction and very effective in operation.

The invention consists in certain parts and 20 details and combinations of the same, as will be fully described hereinafter, and then pointed out in the claim.

Reference is to be had to the accompanying 25 drawings, forming a part of this specification, in which similar letters of reference indicate corresponding parts in all the figures.

Figure 1 is a side elevation of the improvement as applied to a sewing-machine, parts of 30 which are in section. Fig. 2 is a front elevation of the same, and Fig. 3 is a section plan view of the same on the lines $\alpha\alpha$ of Fig. 2.

The sewing-machine shown in the drawings 35 in connection with the tension is fully shown and described in the application above referred to, and hence a further description of the parts not relating to the tension is not deemed necessary.

The sewing-machine is provided with a casting, A, on which is hinged the bed-plate A', supporting the arm E, carrying on its front end the head E³, on which the tension devices H H 40 are located.

The head E³ is provided with a removable front plate, E⁴, and in the said head E³ is held to slide the needle-bar F, provided with a lug, F⁶, operating the take-up mechanism G, located

45 above the tension devices H H, also held on the said head E³. Each of the tension devices H consists of the horizontal spring-bar H', fastened by one end on the head E³ and fitting

with its other half-round end into a correspondingly-shaped head, H², secured to the 50 head E³ and having a notch, H³, in its upper edge, through which the needle-thread T or T', respectively, enters and then passes between the head H² and the half-round end of the 55 spring-bar H'. The threads then pass upward to the take-up mechanism G.

The pressure between the head H² and the half-round end of the spring-bar H' is regulated by a bolt and nut, H⁴, or other means acting on the said spring-bar H'. 60

The operation is as follows: The needle-bar F derives its vertical sliding motion from the main shaft, and in its descent acts on the take-up mechanism and carries it downward, thus permitting the lower ends of the threads T and 65 T' to follow the needles held on the said needle-bar F. When the latter is on its upward stroke, then the take-up mechanism G exerts a pull on the threads T and T', which are thus 70 unwound from their respective bobbins and are pulled between the heads H² and the half-round ends of the spring-bars H', thus giving resistance to the threads. The lower ends of the threads T and T' are held in the cloth to be sewed, and the tension mechanisms H H 75 prevent a too rapid unwinding of the threads from their respective bobbins, and also prevent breakage of the threads.

The tension device H can be used single or double, as desired. 80

Having thus fully described my invention, I claim as new and desire to secure by Letters Patent—

The combination, with the head of a sewing-machine, of the spring-plate H', secured to 85 the said head and having its free end half-round, and the correspondingly-shaped head H², secured to the sewing-machine head and receiving the half-round end of the spring-plate H', the said head H² being provided with 90 the notch H³ in its upper edge, substantially as shown and described.

EMILIO QUEROL Y DELGADO.
